UNITED STATES PATENT OFFICE.

LOUIS HILL, OF AKRON, OHIO.

SAFETY CUT-OFF MECHANISM FOR GAS BURNERS.

Application filed November 1, 1923. Serial No. 672,043.

My invention relates to safety cut off mechanism for gas burners, my more particular purpose being to provide a device of this type made up of a small number of parts easily manufactured and assembled and readily standardized, the operation of the parts being such that whenever the burner flame is extinguished by a gust of wind or other analogous accidental cause, so 10 as to leave gas flowing through the burner, the supply of gas to the burner is automatically cut off.

A special object of my invention is to so construct and arrange the various parts that 15 my device as a whole may be treated as an attachment, and as such may be readily placed upon or removed from existing gas burners of many different kinds, now in common use, but without the necessity for any 20 substantial mechanical change in the burner and without the use of any tools, except, if necessary, those of the simplest kind.

A further purpose of my invention is the provision of alarm mechanism of simple 25 form, for the purpose of indicating to the operator certain changes taking place in the condition of the apparatus while the latter is in use, or is being set for use.

Reference is made to the accompanying 30 drawing forming a part of this specification, and in which like reference characters indicate like parts throughout the several figures.

Figure 1 is a fragmentary plan view of a 35 burner suitable for an ordinary gas stove, and provided with a burner equipped with my improved safety cut off mechanism.

Figure 2 is a side elevation of the mechanism appearing in Figure 1.

Figure 3 is a fragmentary section through 40 the casing used for holding the spring operated plunger and parts immediately associated therewith, used for controlling the gas valve.

Figure 4 is a section on the line 4—4 of 45 Figure 3, looking in the direction indicated by the arrows.

The burner appears at 5, and receives its 50 supply of gas through the mixing tube 6. The jet pipe appears at 7, and delivers gas into the mixing tube. A gas pipe 8 is connected with the jet pipe 7, and serves as a source of supply.

The jet pipe 7 is provided with a valve 9, 55 having a revoluble valve plug 10, and car-

ried by this valve plug is a handle 11, whereby it may be actuated, in the usual manner.

When the handle 11 occupies the position indicated for it by full lines in Figure 1, the gas is cut off. When, however, the handle 60 is turned so as to occupy the position indicated for it by dotted lines in Figure 1, gas is free to flow through the jet pipe 7 into the mixing tube 6, and thence into the burner. Thus the operator, in order to turn the gas 65 on or off, merely grasps the handle 11 and turns it from one to the other of its two normal positions by full and dotted lines in Figure 1.

Encircling the handle 11 is a collar 12, and 70 connected with this collar, by means of two links 13 and 14, is a sliding rod 15. This sliding rod extends into and is slidably relatively to a casing 16 of substantially cylindrical form. Slidably mounted within the 75 casing 16, and secured rigidly to the sliding rod 15, is a piston 17. This piston is engaged by the adjacent end of a spiral spring 18, which is housed within the casing. The spring is always under tension, and tends to 80 force the piston 17 and consequently the sliding rod 15 to the right according to Figure 3.

The casing 16 carries an arm 19 mounted rigidly upon it, and secured to this arm 19 is a thermostatic bar 20, held in position 85 by a fastening 21.

Extending from the casing 16 and integral therewith is a lug 22, shown more particularly in Figure 4. Journaled upon this lug is a rocking lever 23, the upper end of 90 which is connected with the adjacent end portion 24 of the thermostatic bar 20. The rocking lever 23 is provided with a lug 25 integral with it, and extending toward the casing 16.

The casing 16 is provided with a slot 26, located in proximity to the lug 25, and so positioned that when the rocking lever 23 is moved from the position indicated for it by full lines in Figure 4 to the position indicated for it by dotted lines in said figure, the lug 25 extends through the slot 26.

The rocking lever is at its lower end provided with a beveled portion 27, and adjacent this portion is a spring arm 28, secured 105 in position by a fastening 29 and carrying a metallic weight 30, serving as bell clapper. The spring arm is further provided with two loops 31 and 32 bent slightly upward as indicated in Figure 4.

The casing 16 is provided with a slot 33 into which the lug 25 extends, as indicated in Figure 4. A small bell 34 is mounted upon the casing 16, in close proximity to the 5 spring arm 28, and in such position as to enable it to be struck by the clapper 30, in the event of the spring arm 28 making a stroke in the right direction for this purpose.

10 Whenever the piston 17 is moved to the left according to Figure 3, due to the movement of the handle 11 from its position indicated by full lines in Figure 1 to its position indicated by dotted lines in said figure, 15 the piston 17 travels past the loop 32, and in so doing pushes this loop slightly outward and then allows it to spring back abruptly, the net result being that the clapper 30 is first moved slowly away from the bell 34 and then caused to strike the bell forcibly, 20 so as to produce an audible sound. This sound is produced at the instant when the piston 17, during its travel to the left according to Figure 3 clears the loop 32, so 25 that this loop can move a slight distance inwardly. The sound of the bell apprises the operator that the piston is at the limit of its travel to the left according to Figure 3, and consequently that the gas is flowing freely through the valve, and in condition 30 to be lighted.

Whenever the handle 11 is thus turned into the position indicated for it by dotted lines and the flow of gas is thus turned on 35 as just described, the tension of the spring 18 tends to shift the piston to the right according to Figure 3, and thus to cause the valve to close, unless the gas be lighted at the burner. Therefore the operator holds 40 the handle 11 in the position indicated for it by dotted lines in Figure 1, and meantime lights the gas. The burner is thus heated, the temperature of the thermostatic bar being raised, so that the upper portion 45 of the bar according to Figure 3 is moved from the position indicated for it by full lines into the position indicated for it by dotted lines in this figure. The result is that the rocking lever 23 is rocked in a 50 counter-clockwise direction, as indicated by full and dotted lines in Figure 4. This movement causes the lug 25 to extend through the slot 26 a sufficient distance to serve, for the time being, as a stop for the 55 piston 17. Thereupon the operator releases the handle 11, which now remains in the position indicated for it by full lines in Figure 1, because the sliding rod 15 can not move to the right according to Figure 3, so long 60 as the piston 17 rests against the lug 25.

The gas continues to flow and to burn as long as the various movable parts occupy the respective positions contemplated for them with the apparatus in the condition 65 just described.

Suppose, next, that the burner flame is extinguished by a gust of wind or in some analogous manner, so as to leave the gas flowing through the burner and escaping unburned. The thermostatic bar 20 now begins to cool rapidly, so that this bar and the rocking lever 23 controllable thereby move from the positions indicated for them by dotted lines in Figures 3 and 4 into the positions indicated for them by full lines 75 in these figures. This movement of the locking lever 23 carries the lug 25 to the left according to Figure 4, and it thereupon releases the piston 17. This causes the sliding rod 15 to move suddenly to the right according to Figures 1 to 3, inclusive, thus abruptly closing the valve by turning the handle 11 in a counter-clockwise direction according to Figure 1, and leaving the handle 11 in the position indicated for it by 80 full lines in this figure.

A shackle 35, shown more particularly in Figures 1 and 2, is provided with a screw bolt 36 and is formed and arranged for use therewith as a coupling. By means of this coupling the casing 16 and parts carried thereby, considered collectively as a unit, may be detachably mounted upon or readily removed from the mixing tube 6. For this purpose my device may be considered as 90 an attachment to be placed upon or removed from gas stoves or analogous apparatus, already in use.

The operation of my device may be readily understood from the foregoing description. 100

In order to light the gas, the operator grasps the handle 11 and turns it in a clockwise direction until the bell rings. Holding the handle in the position it now occupies, the operator lights the gas and waits until the bell rings again, whereupon he releases the handle 11. The gas now continues to burn until shut off by a movement of the handle. 110

The handle 11 may be operated by hand at any time, to either open or close the valve.

I do not limit myself to the precise mechanism here illustrated and described, as variations may be made therein without departing from my invention, the scope of which is commensurate with my claims. 115

Having thus described my invention, what I claim as new and desire to secure by Letters Patent is as follows:

1. A device of the character described, comprising a gas burner, a mixing tube connected therewith, a jet pipe extending into said mixing tube for supplying gas through said mixing tube to said burner, a valve mounted upon said jet pipe, mechanism connected with said valve for closing the same, a spring connected with said last mentioned mechanism, a casing in which said spring is housed, said casing being provided with an 120

- opening, a lever carried by said casing and journaled to rock, said lever being provided with a lug located adjacent said opening in said casing, so that said lever can prevent 5 said spring from causing the closure of said valve, and a thermostatic bar mounted upon said casing and connected with said lever for the purpose of rocking said lever, the thermostatic bar being located adjacent said 10 burner in order to be actuated by heat therefrom.
2. A device of the character described comprising a gas burner, a jet pipe for supplying gas to said gas burner, a valve mounted upon said jet pipe for controlling the flow of gas therethrough, mechanism connected with said valve for closing the same, a spring connected with said last mentioned 15 mechanism, a casing in which said spring is housed, said casing being provided with an opening, a lever mounted upon said casing and journaled to rock, said lever being provided with a lug located adjacent said opening in said casing, said lever being so located 20 as to enable said lug to prevent said spring from causing the closure of said valve; and heat controlled mechanism carried by said 25
- opening, a lever carried by said casing and journaled to rock, said lever being provided with a lug located adjacent said opening in said casing, so that said lever can prevent 5 said spring from causing the closure of said valve, and a thermostatic bar mounted upon said casing and connected with said lever for the purpose of actuating said lever.
3. A device of the character described comprising a burner, a jet pipe connected with said burner for supplying gas thereto, a valve for opening and closing said jet pipe, a casing mounted adjacent said valve and having a substantially tubular form, a 30 sliding rod sliding into said casing and movable relatively thereto, connections from said sliding rod to said valve for enabling said valve to be actuated by said sliding rod, a spring having a general cylindrical form and 35 fitted into said casing, said spring being connected with said sliding rod in order to move said sliding rod and thus close said valve, a lever for holding said sliding rod in a predetermined position against the tension of said spring, and thermostatic mechanism connected with said lever for the purpose of releasing said spring, said thermostatic mechanism being located adjacent said burner and controllable by heat therefrom. 40
- Signed at Akron, in the county of Summit and State of Ohio, this 30th day of October, 1923.

LOUIS HILL.
